[57] CLAIM

The ornamental design for a household storage rack or similar article, as shown and described.

DESCRIPTION

FIG. 1 is a perspective view of a household storage rack or similar article showing my new design;
FIG. 2 is a side elevational view thereof, the opposite side being substantially a mirror image of that shown;
FIG. 3 is an end elevational view thereof, the opposite end being substantially a mirror image of that shown;
and
FIG. 4 is a top plan view thereof, the bottom being substantially plain and unornamented.

FIG.1

FIG. 4
